UNITED STATES PATENT OFFICE.

THOMAS MATHEWS, DECEASED, BY ANNIE MATHEWS, OF LEICESTER, AND HARRY BUCKINGHAM, OF LONDON, ENGLAND, ADMINISTRATORS.

ADVERTISING AND DISPLAY DEVICE.

1,421,277.

Specification of Letters Patent. Patented June 27, 1922.

Application filed April 12, 1921. Serial No. 460,637.

To all whom it may concern:

Be it known that we, ANNIE MATHEWS and HARRY BUCKINGHAM, subjects of the King of Great Britain, residing at Leices-
ter, England, and London, England, respec-
tively, are the duly appointed administra-
tors of the estate of THOMAS MATHEWS, de-
ceased, late a subject of the King of Great
Britain, the latter having invented certain
new and useful Improvements in Advertising
and Display Devices, of which the following
is a specification, reference being had there-
in to the accompanying drawing.

This invention relates to advertising and
display devices of the kind adapted to fold
or collapse to a flat condition for packing
and to open and be self-supporting in an
erect position for display.

The present invention comprises an im-
proved form of device of the above men-
tioned kind wherein a front member stands
up in front of a back member on a base, the
improvement being in connection with a
combined strut for supporting the structure
in the display position.

According to the invention, a back mem-
ber and a front member hingedly attached
to a base have combined with them a strut
which is vertically hinged to the rear of the
front member and works in a slot formed
in the back member or back and base mem-
bers, said strut, when the device is erected,
projecting to the rear thereof to form a
support therefor and having a notch or
equivalent to engage with the back member
and maintain it erect.

When the device is collapsed the front
and back members lie close together and the
strut folds down upon the rear of the back
member.

In the accompanying drawings two spe-
cific forms of display devices are shown as
examples of the invention.

Referring to the drawings:—

Figure 1 is a back view of one device
shown in the folded or collapsed condition.

Figure 2 is a side elevation of the device
in erected form viewed from right of Fig-
ure 3.

Figure 3 is a sectional plan taken on the
line $a-a$ of Figure 1 but showing the de-
vice reversed and in erected form.

Figure 4 is a rear view of the other de-
vice in the folded or flat condition.

Figure 5 is a side view of the same in 55
erected condition.

Figure 6 is a sectional plan on the line
 $b-b$ of Figure 4 the device being shown
reversed and in erected form.

In the concrete example shown in Fig- 60
ures 1, 2 and 3, a flat back member 1 of
suitable shape is hingedly united at 2 to the
rear edge of a flat base 3 so that by turn-
ing the latter down, the two parts can be
brought into alignment, or by raising the 65
base it can be brought at right angles rela-
tively to the back as shown in Figure 2.
Hingedly attached at 4 to the upper face
of the base 3 and situated some distance
away from the back member 1 is a flat front 70
member 5 adapted, when the device is erect-
ed to stand upright in front of and parallel
to the back member. When the base and
back are flattened out, the front 5 lies with
its back against the face of the back mem- 75
ber as shown in Figure 1.

A strut 6 consisting of a piece of flat card
board and attached by a vertical hinge 7 to
the back of the front member 5, is shaped so
that its free end forms a foot 8 at the lower 80
extremity while on its upper edge it has an
upstanding shoulder 9 (Figure 1) in front
of which a short vertical slot 10 is made.
The strut extends through a vertical slot 11
in the back member 1 the upper end 12 of 85
which slot is adapted to be engaged with the
slot 10 in the strut 6 by a downward move-
ment of the back after the latter has been
moved rearward to the extent determined by
the shoulder 9 on the strut 6. To collapse 90
the device, the back member 1 is moved up-
wards to disengage it from the strut and is
then moved forward to bring the back, base
3 and front member 5 to the flat condition
after which the strut 6 is turned down to one 95
side on the back as shown in Figure 1.

The slot 11 in the back member 1 is con-
tinued into the base 3 as shown at 11^a (Fig-
ures 1 and 3) to enable the folding or col-
lapsing movements of the back and base 100
members to take place.

The constructional embodiment shown in
Figures 4 to 6 is generally similar to the one
just described the back member 13 being
hinged to a base 14 at 15, to which base is 105
also hingedly attached at 16 a front member
17. In this case however, two struts 18 are
hinged vertically at 19 on the front member

17 and extend through an opening 20 in the back 13 which opening is continued into the base 14. The struts have upstanding projections 21 formed on their upper edge at the rear.

When the device is flattened out as shown in Figure 4, the back 13 and front member 17 lie close together, the base 14 being in alignment with the back and the two struts 18 turned down flat upon the aligned back and base. To open and erect the device, it is held by the back 13, which when the lower edge of the base rests upon a table or other support, is pressed downwards thereby turning the base to a position at right angles to the back and front members and throwing the latter in advance of the back as shown in Figures 5 and 6. The two struts are drawn partly through the opening 20 and assume divergent positions to support the device while the projections 21 maintain the back 13 from falling rearwards.

The members composing the device may be got up in any appropriate style. For example, the members 1, 5, 13, and 17 may have, upon their front faces, representations of articles of merchandise or the like which it is desired to display or advertise, or these members may be shaped and printed to represent such articles.

What is claimed is:—

1. A display device of the kind herein referred to, comprising, a base, a back member and a front member hingedly attached to the base, and a strut vertically hinged to the rear of the front member and arranged to work in a slot or opening formed in the base

and back member, said strut when the device is erected projecting to the rear thereof to form a support therefor and engaging with the back member to maintain it erect.

2. A display device of the kind herein referred to, comprising, a base, a back member and a front member hingedly attached to the base, a strut vertically hinged to the rear of the front member and arranged to work in a slot or opening formed in the base and back members, said strut when the device is erected projecting to the rear thereof to form a support therefor, and a shoulder on the strut to engage the back member and prevent it falling rearwards from the upright position.

3. A display device of the kind herein referred to, comprising, a base, a back member and a front member hingedly attached to the base, a pair of struts vertically hinged to the rear of the front member and arranged to work in an opening formed in the base and back members, said struts when the device is erected projecting to the rear thereof to form a support therefor, and a shoulder on each strut to engage the back member and prevent it falling rearwards from the upright position.

In testimony whereof we affix our signatures in presence of two witnesses.

ANNIE MATHEWS,
HARRY BUCKINGHAM,
*Administrators of the Estate of Thomas
Mathews, Deceased.*

Witnesses:

E. N. LEWIS,
GEORGE LESTER.
